UNITED STATES PATENT OFFICE.

JOHN M. GANTVOORT, OF BEACON, NEW YORK.

LOADING DEVICE FOR BAKERS' RACKS.

Application filed March 25, 1922. Serial No. 546,759.

My invention relates to loading devices for bakers' racks, and particularly for racks adapted to be used with ovens of the general type shown in my Patent No. 1,135,172, 5 April 13, 1915. The object of my invention is to provide means for bringing the oven shelves carried by the rack to a convenient height for loading.

In the accompanying drawings—

10 Fig. 1 is a side elevation, partially in section, of a loading table in which my invention is embodied in one form,

Fig. 2 is a section on the line 2—2, Fig. 1;

15 Fig. 3 is a side elevation, partially in section, of a modified arrangement;

Fig. 4 is an end elevation of the table alone; and

Fig. 5 is a section on the line 5—5, Fig. 3.

In the practical operation of ovens of the 20 type shown in my patent above mentioned, it is customary to use racks upon which the several oven shelves are supported in superposed relation at elevations of from 1½ to 6 feet above the floor level. While it is fairly 25 easy to load the baking pans upon the shelves in intermediate position, it is awkward and fatiguing for the workmen to load the pans upon the shelves at the top and bottom of the racks. By the present invention 30 I provide means by which all of the shelves of the rack may be loaded at a height convenient for the workmen.

In the embodiment of my invention shown in Figs. 1 and 2, the rack 10 is supported 35 by trolleys 11 and 12 from an over-head rail 13, after the fashion illustrated in my application of even date herewith. The present invention, however, is not limited in its utility to an installation of this type, and may 40 be used to advantage where racks of the standard type, supported on running wheels, are employed in the shop. The loading table proper comprises end frames 14 and longitudinal rails 15 and 16 properly spaced to 45 receive the wheels 17 of an oven shelf 18. The rails 15 and 16 are unobstructed at one end, but are provided with stops 19 at their other ends to prevent over-running by the shelf. The end frames 14 carry guide 50 brackets 20 shaped to the four guide posts 21 on which they slide. The brackets are also provided with lugs 22, to which the ends of cables 23 may be attached. The cables pass over sheaves 24 at the top of the posts, and 55 down to the counterweights 25 which work therein. Any suitable latching device may

be used to hold the table at desired elevations. To illustrate the idea, one of the posts is provided with a series of recesses 26, into which takes a latch 27 on the corresponding 60 corner bracket.

Assuming the rack 10 to have been properly positioned with respect to the table, as illustrated in Fig. 1, the table may be brought to the elevation of the top shelf 18 65 on the rack and halted by means of the latch 27. The top oven shelf may now be run out on the tracks 15 of the table, and the latter lowered to a convenient level for loading. When the loading operation is finished, the 70 shelf and loading table may be again raised to the proper level with respect to the rack and the loaded shelf returned to the rack. Similarly the bottom shelf may be run out on the lowered table and the latter lifted to a 75 convenient loading position, after which the table is again depressed and the loaded shelf returned to the rack. In a system such as that shown, where the rack travels on the trolley 13, the loading table is depressed below the rack after the latter has been loaded, whereupon an unobstructed passageway 80 between the posts is afforded for the advance of the rack to a point beyond the loading table. 85

A modified embodiment of the idea is illustrated in Figs. 3, 4 and 5. In this construction the loading table is stationary and the rack is moved bodily up and down with respect to the table. Thus, the table 28 is 90 supported in fixed position on the frame 29. The rack 10 is here shown supported by its trolleys 11 and 12 on a vertically movable section 30 of the track supported by a cable 31. By paying out the cable 31, the track 95 section 30 and rack 10 are bodily lowered, preferably through a guideway 32, which serves not only to maintain the rack in exact position with respect to the table, but also to retain the trolleys on the track section. 100 As the rack is lowered, each shelf successively may be run out on the table 28, filled and run back on the rack, until the loading operation is completed.

I have, however, indicated the table as of 105 sufficient length to receive two shelves in series from the rack. The more remote portion of the table comprises tracks 33 pivoted off center at 34 to the standards 35 of the frame. In dropped position the tracks 33 110 are adapted to make joint with a lower set of tracks 36, spaced downward a distance

corresponding to the spacing of the tracks on the rack. By this arrangement it is possible to lower the rack while one shelf is being loaded, the latter then being forced back on the section 33 of the table by the withdrawal of the succeeding empty shelf from the rack to the loading table. The loaded shelf automatically tips down the rail sections 33 of the table, and owing to the inclination of the latter, automatically runs onto the rails 36, and thence to the rack, thus returning to the position on the latter from which it was originally withdrawn. The operation is repeated for each succeeding shelf as the rack is gradually lowered step by step, until the topmost shelf is withdrawn and loaded. This shelf is returned direct from the table 28 to the rack. It may be pointed out that upon the tipping of the rail section 33 of the table, the shelf thereon does not immediately advance, but is retained by the block 37 against which the end piece 38 of the shelf bears. The length of the block 37 is such that the shelf does not escape the rails 33 until the latter have reached their full downward inclination and rest upon the return rails. A sufficient impulse is thus given to the shelf to travel to its return position on the rack. If desired, the track 36 may be somewhat inclined toward the rack throughout its entire length.

Whether the loading table be lifted and lowered as in Figs. 1 and 2, or the rack be bodily lifted and lowered, as in the construction last described, it is obvious that the loading operation is performed at a level convenient for the workmen. The loading of the baking pans on the shelves is not only more easily and accurately done, but the operation is also expedited.

The lifting and lowering operations may be accomplished in various ways—for example, by electrically controlled motors, etc. The invention is not particularly concerned with this. Modifications in details of construction and arrangement will also readily occur to those dealing with the problem, which do not, however, depart from what I claim as my invention.

I claim:—

1. A baker's installation, comprising a rack adapted to accommodate a series of removable superposed baking shelves thereon, an overhead rail having a vertically displaceable section, means supporting the rack for travel on said rail and for temporary stationary support on said displaceable section,

a loading table adjacent the rack while so supported by the rail section, and means for vertically displacing the rail section to bring successive shelves on the rack into register with the table so that they may run off the rack onto the table for loading, said table including a tiltable shelf support down which a loaded shelf may run by gravity to the rack.

2. A baker's installation, comprising a rack adapted to accommodate a series of removable superposed baking shelves thereon, an overhead rail having a vertically displaceable section, means supporting the rack for travel on said rail and for temporary stationary support on said displaceable section, a loading table adjacent the rack while so supported by the rail section, and means for vertically displacing the rail section to bring successive shelves on the rack into register with the table so that they may be run off the rack onto the table for loading, said table having upper and lower shelf supports, and means for returning a shelf to the rack by way of the lower support after it has been loaded on the upper support.

3. A baker's installation, comprising a rack adapted to accommodate a series of removable superposed baking shelves thereon, an overhead rail having a vertically displaceable section, means supporting the rack for travel on said rail and for temporary stationary support on said displaceable section, a loading table adjacent the rack while so supported by the rail section, and means for vertically displacing the rail section to bring successive shelves on the rack into register with the table so that they may be run off the rack onto the table for loading, said table having upper and lower shelf supports, a portion of said upper support remote from the rack being tiltable to return a shelf to the rack by way of the lower support.

4. In a baker's installation, a loading table having upper and lower levels, a rack adapted to be positioned adjacent the table and having a series of superposed removable shelves adapted to be withdrawn serially from the rack to the upper level of the loading table, and means for returning the shelves to the rack by way of the lower level of the table, said means comprising a tiltable section of the table upper level adapted to lead a rack by gravity to the lower level of the table.

In testimony whereof I have signed my name to this specification.

JOHN M. GANTVOORT.
